Primary Examiner — Rhea Shields(74) *Attorney, Agent, or Firm* — Greenblum & Bernstein, P.L.C.(57) **CLAIM**

I claim the ornamental design for a service cart, as shown and described.

DESCRIPTION

FIG. 1 shows a top front side perspective view a service cart according to the invention;

FIG. 2 shows a front view of FIG. 1;

FIG. 3 shows a back view of FIG. 1;

FIG. 4 shows a right side view of FIG. 1;

FIG. 5 shows a left side view of FIG. 1;

FIG. 6 shows a top view of FIG. 1; and,

FIG. 7 shows a bottom view of FIG. 1.

Any surfaces of the design not shown, including interior surfaces and any surfaces shown in broken lines, form no part of the claimed invention.

1 Claim, 7 Drawing Sheets(56)
